UNITED STATES PATENT OFFICE.

HARRISON S. TAFT, OF SEATTLE, WASHINGTON.

APPARATUS FOR CONSTRUCTING CONCRETE COLUMNS.

1,139,384.

Specification of Letters Patent.

Patented May 11, 1915.

Application filed May 22, 1913. Serial No. 769,212.

To all whom it may concern:

Be it known that I, HARRISON S. TAFT, a citizen of the United States, and resident of Seattle, in the county of King and State of Washington, have invented new and useful Improvements in Apparatus for Constructing Concrete Columns, of which the following is a specification.

My invention relates to the construction of columns of concrete or reinforced concrete, and has for its particular object the facilitation of under-water operations of this character in situations where the depth of water renders caisson work difficult or impossible.

The invention consists in apparatus adapted to the construction of either solid or hollow concrete piles or columns.

In the drawings hereto annexed, which illustrate my invention and the mode of operation,—

Figures 1, 1^a and 1^b show in section the lower, middle and upper parts of a concrete column or pile and the apparatus for building the same, (Fig. 1^b being on a larger scale than 1, or 1^a); Fig. 2 is a cross section (on a larger scale) on the line 2—2 of Fig. 1^a; Fig. 3 is a cross section on a larger scale at the line 3—3 of Fig. 1; Fig. 4 is a vertical section on still larger scale of a perforated exterior guide; Fig. 5 is a vertical section on the same scale as Fig. 4 of the interior guide for the center core form of the column; Fig. 6 is a cross section taken on line 6—6 of Fig. 1^b; Fig. 7 shows a plan view of the arrangement of the reinforcement of the conical hollow head of the column; and Fig. 8 is a vertical sectional view of a concrete column constructing apparatus showing the method of introducing the concrete into the mold or form.

Referring to Figs. 1, 1^a, 1^b and 8: a cylindrical sheet pile or coffer A, which is put together in sections, is sunk into the bottom material M to such a distance that the water in the interior of the coffer A may be readily pumped out and the interior kept water-free. Any suitable sheet piling material may be used to build the coffer A, such as, for instance, "Lackawanna" sheet piling. The coffer A is braced internally by the bracing rings A' which are wedged into place and preferably held together and spaced by means of hangers, such as a'. Into the interior of the coffer A the outer form C, which is composed of sections, is

lowered into place and the lower section or cutting edge C' driven or sunk into the bottom material M to a suitable distance either before, during, or after, the excavating operation. Angle iron rings C² may be employed to join the sections of this outer form together. The form C being placed within the outer coffer A, the interior of the form C may be pumped out and the bottom material M excavated therefrom as far as desired, and then, if necessary, sub-piles P are driven into the bottom material.

An apparatus for driving the sub-piling will not be described here since it forms the subject matter of an application for United States Letters Patent filed by me concurrently herewith and serially numbered 769,215.

When the sub-piles P have been driven and prepared for the deposition of concrete, the concrete is poured in to form a base B, which embraces and binds the sub-piling P; thereupon, the form D, or a section of it, may be lowered into place. The conical termination D⁰ of the form D should preferably be supported and centered so as to stand above the heads of the piles P and be spaced therefrom. If desired, reinforcing metal may be incorporated into the base B in the usual manner so as to lock or anchor the superincumbent mass to the base. Reinforcing material for the column or pile itself will consist of rods or metal strips which may be formed in various ways. A mode of arranging the reinforcement for a hollow pile is indicated in Figs. 1^a and 1^b, where a cage is formed of vertical rods H and spirally arranged rods I. Outside of this cage-like arrangement other parallel vertical rods G may be employed.

The lower course of metal reinforcement, being in place, concrete is deposited on the top of the base B and around the heads of the piles P which were left projecting above the top of the base B, and thereupon, the inner form is lowered into place. This inner form is generally designated as D in Fig. 1, and consists of a hollow metal shell put together in sections and provided with an interior spreading or bracing device, which will presently be described. The lowermost section of the interior form D will have preferably a conical termination as shown at D⁰, Fig. 1; this lower section need not be permanently attached to the section next above it, so that when the interior

form is finally removed (as presumably it will be) from the column or pile, the conical form at D⁹ will remain in place.

The structure of the inner form D is shown in Figs. 1^a and 3. An outer shell D' of comparatively thin metal is reinforced from within by several segmental metal sections D², which are provided with angle iron reinforcements D³ to which are attached links D⁴ which extend radially to a nut D⁵, which is threaded to receive a threaded portion on the central rod D⁶; the nuts D⁵ are right-handed in some instances and left-handed in others, as indicated in Fig. 1^a, so that when the rod D⁶ is turned, the left hand threaded nuts will be drawn toward the right hand threaded nuts and the links D⁴ moved toggle-wise to brace the reinforcing segments D² firmly against the interior of the comparatively thin shell D'. For convenience, metal ladder rungs as D⁸ may be secured to one of these segments D² and plates or platforms as D⁷, to others. These adjuncts serve to strengthen the reinforcing segments D² and also provide facilities for men who may have to descend into the inner form generally designated as D. The thin shell D' is merely a skin over the effective structure of the form itself, and removal of "the form" D, may, and usually would, mean, removal of the structure within the shell D', which in most cases will be left in the pile.

The apparatus for building the concrete column in the annular space between the outer form C and the inner form D, comprises as its principal functional factor the sliding perforated exterior guide E which is a metal tube or box provided with a large number of perforations which preferably slant downward and outward; this tube or box is of less diameter than the interior of the outer form C and has angle iron ribs extending from top to bottom which bear against the interior of the outer form C. The structure of the perforated sliding exterior guide is shown in Figs. 3 and 4. The perforated portion is made in segments E' which are joined to the angle iron ribs E². This perforated exterior guide E serves and assists in the proper distribution of concrete within the form C. Also it serves as a holder for the interior cage-like reinforcement composed of the reinforcing members H—I (see Figs. 1 and 3). This cage-like reinforcement structure is cylindrical in form and, as illustrated in Fig. 1, extends vertically throughout the body of the column. The dimensions of this cylindrical cage-like reinforcement H—I are such as to fit easily inside the cylindrical guide E which consequently holds the cage reinforcement H—I properly centered while concrete is being deposited around it to embed the said reinforcement in the column.

The guide E may also be adapted to hold outer vertical reinforcement such as rods G, as follows: A hoop E⁴ (see Figs. 3 and 4) is secured to the inside of the cylindrical guide E preferably at or near the upper edge thereof and is spaced from the inner surface of the cylindrical segments E' by means of blocks E⁵ between which are left spaces for the accommodation of the vertically disposed reinforcement rods G. These rods being slipped into their appropriate holes between the blocks E⁵, are held in proper position while concrete is being deposited around them, and as the guide E slides upward new rods G can be inserted between the blocks E⁵ as required. The proportions of the perforated guide E are such that the cage-like reinforcement H, I, is embraced by it while the angles E² slide on the inner surface of the outer form C leaving a space between the shell segments E' and the said form for the deposition of grout against the inner surface of the form C. In order to hold the inner form D centrally with the reinforcing metal H, I, and thus with the external form C, I provide in the apparatus for building hollow columns or piles an interior guide F (Fig. 1), shown more in detail in Fig. 5. This guide consists of a segmentally built cylindrical shell composed of members F' which are joined together by means of plates F² which project both inside and outside of the cylindrical shell composed of the segments F'. These plates F² bear against the inner form D and also against the metal reinforcement H, I, so that the former is kept truly centered during the deposition of concrete which might otherwise displace or distort it. Ropes or wires L serve to suspend and manipulate the interior guide F.

The inner form D may be built up in sections as work progresses, the inner reinforcement H, I, lowered into place outside the interior guide F and inside the perforated exterior guide E, and if desired, reinforcing rods G are inserted between the spacer blocks E⁵ provided as above described in the guide E. Concrete properly mixed is sent down through tubes in a manner hereinafter described and fills the space between the interior form D and exterior form C, passing by the interior guide F and entering the interior of the perforated guide E. The perforations allow the fine material to pass outside, filling the space between the guide E and the exterior form C; the forcible descent of the concrete material exercises an effective tamping action which may be supplemented by movement of the guide E which is raised by degrees as the deposit of concrete progresses; the interior guide F being raised in a corresponding manner so as to perform its function as a spacing and centering contrivance for the inner form D.

In this manner and with the apparatus hereinabove described, the concrete column or pile is built from its foundation to the desired height. In completing the column 5 and before the head or capital is built thereon, if a column be hollow as shown in Figs. 1, 1^a, and 1^b, the hollow core is completed by placing a conical cap at D¹⁰ over the axial opening in the column and placing around 10 this cap D¹⁰ the conical or conoidal reinforcement composed of circumferential and longitudinal reinforced metal O and N which is prepared for the reinforcement of the conical head shown in Fig. 1^b. This 15 conical head is preferably provided with a central solid core of concrete C'' and is molded with webs R which extend from the core C'' to the conical shell C.

The manner in which concrete is deposited in the course of constructing the column or pile is indicated in Fig. 8, which shows a simpler apparatus for the construction of a solid concrete pile. In this apparatus the coffer A and form C, sub-piling P 20 and foundation concrete B set in the bottom material M are all substantially as described hereinabove. The reinforcing material (not shown in Fig. 8) will preferably be introduced as shown in Figs. 1, 1^a and 3. 25 Since the concrete will be introduced into the center of the column in order to form the solid pile, it will not be necessary to provide an interior guide such as shown in Fig. 5. The perforated guide E, however, performs 30 its function in the construction of the solid pile, first, in keeping the reinforcing metal in place, and second, in straining the fine material through its perforations, so as to produce a suitable surface at the 35 outside of the concrete column. The concrete is deposited in the form C by means of the sectional tube T into the top of which concrete is delivered from the hopper or chute, as S. As the column progresses in 40 construction from below upward, sections of the tube T will be removed and hoisted out of the form C. In the construction of the hollow pile or column above described 45 similar tubes will be employed of suitable 50 size and shape to deliver the material into the space between the inner and outer forms.

The mode of molding and forming the 55 hollow conical heads is too well known to engineers acquainted with concrete construction to require detailed description.

Apparatus substantially as above described may be constructed and its parts so shaped as to adapt it to the formation of 60 polygonal piles as well as cylindrical.

What I claim and desire to secure by Letters Patent is:

1. In apparatus for constructing reinforced concrete columns, the combination of 65 an outer inclosing form, and a guide, fitted

to slide in said outer form, and comprising means to embrace and hold in position the reinforcing members for the column.

2. In apparatus for constructing reinforced concrete columns, the combination of 70 an outer inclosing form, and a perforated guide, fitted to slide in said outer form and comprising means to embrace and hold in position the reinforcing members for the column. 75

3. In apparatus for constructing concrete columns, the combination of an outer inclosing form, a guide, fitted to slide in 80 said inclosing form, and provided with spacer strips to bear on the interior of said form, said guide also comprising means to embrace and hold in position the reinforcing members for the column.

4. In apparatus for constructing concrete columns, the combination of an outer 85 inclosing form, a perforated guide, fitted to slide in said inclosing form and provided with spacer strips to bear on the interior of said form, said guide also comprising means to embrace and hold in position the reinforcing members for the column. 90

5. In apparatus for constructing reinforced concrete columns, the combination of an outer inclosing form, and a guide, fitted to slide in 95 said outer form, and comprising means to embrace and hold in position the reinforcing members for the column, and a water excluding coffer surrounding the said outer inclosing form.

6. In apparatus for constructing reinforced concrete columns, the combination of an outer inclosing form, and a perforated guide, fitted to slide in said outer form, and comprising means to embrace and hold in position the reinforcing members for 100 the column, and a water excluding coffer surrounding the said outer inclosing form. 105

7. In apparatus for constructing reinforced concrete columns, the combination of an outer inclosing form, comprising detachable sections, and a guide, fitted to slide in 110 said outer form, and comprising means to embrace and hold in position the reinforcing members for the column.

8. In apparatus for constructing reinforced concrete columns, the combination of an outer inclosing form, comprising detachable sections, and a perforated guide, fitted to slide in 115 said outer form, and comprising means to embrace and hold in position the reinforcing members for the column. 120

9. In apparatus for constructing reinforced concrete columns, the combination of an outer inclosing form, comprising detachable sections, and a guide, fitted to slide in 125 said inclosing form, and provided with spacer strips to bear on the interior of said form, said guide also comprising means to embrace and hold in position the reinforcing members for the column. 130

10. In apparatus for constructing reinforced concrete columns, the combination of an outer inclosing form, comprising detachable sections, and a perforated guide, fitted to slide in said inclosing form, and provided with spacer strips to bear on the interior of said form, said guide also comprising means to embrace and hold in position the reinforcing members for the column. 70
11. In apparatus for constructing reinforced concrete columns, the combination of an outer inclosing form, comprising detachable sections, and a guide, fitted to slide in said outer form, and comprising means to embrace and hold in position the reinforcing members for the column, and a water excluding coffer surrounding the said outer inclosing form. 75
12. In apparatus for constructing reinforced concrete columns, the combination of an outer inclosing form, comprising detachable sections, and a perforated guide, fitted to slide in said outer form, and comprising means to embrace and hold in position the reinforcing members for the column, and a water excluding coffer surrounding the said inclosing form. 80
13. In apparatus for constructing concrete columns, the combination of an outer inclosing form, an outer guide, fitted to slide in said outer form, and comprising means to embrace and hold in position the reinforcing members for the column, an inner guide fitted to slide within said reinforcing means, and to embrace and slide upon an inner form, and said inner form. 85
14. In apparatus for constructing concrete columns, the combination of an outer inclosing form, an outer perforated guide, fitted to slide in said outer form, and comprising means to embrace and hold in position the reinforcing members for the column, an inner guide, fitted to slide within said reinforcing means and to embrace and slide upon an inner form, and said inner form. 90
15. In apparatus for constructing concrete columns, the combination of an outer inclosing form, an outer guide, fitted to slide in said outer form, and provided with spacer strips to bear on the interior of said form, said outer guide also comprising means to embrace and hold in position the reinforcing members for the column, an inner guide, provided with spacer strips on the inside and outside to bear and slide respectively on an inner form and the reinforcing members, and said inner form. 95
16. In apparatus for constructing concrete columns, the combination of an outer inclosing form, an outer perforated guide, fitted to slide in said outer form, and provided with spacer strips to bear on the interior of said form, said outer guide also comprising means to embrace and hold in position the reinforcing members for the column, an inner guide, provided with spacer strips on the inside and outside to bear and slide respectively on an inner form and the reinforcing members, and said inner form, and a water excluding coffer surrounding the said outer inclosing form. 100
17. In apparatus for constructing concrete columns, the combination of an outer inclosing form, an outer guide, fitted to slide in said outer form, and comprising means to embrace and hold in position the reinforcing members for the column, an inner guide, fitted to slide within said reinforcing means, and to embrace and slide upon an inner form, and said inner form, and a water excluding coffer surrounding the said outer inclosing form. 105
18. In apparatus for constructing concrete columns, the combination of an outer inclosing form, an outer perforated guide, fitted to slide in said outer form, and comprising means to embrace and hold in position the reinforcing members for the column, an inner guide, fitted to slide within said reinforcing means, and to embrace and slide upon an inner form, and said inner form, and a water excluding coffer surrounding the said outer inclosing form. 110
19. In apparatus for constructing concrete columns, the combination of an outer inclosing form, comprising detachable sections, an outer guide, fitted to slide in said outer form and comprising means to embrace and hold in position the reinforcing members for the column, an inner guide, fitted to slide within said reinforcing means, and to embrace and slide upon an inner form, and said inner form. 115
20. In apparatus for constructing concrete columns, the combination of an outer inclosing form, comprising detachable sections, an outer perforated guide, fitted to slide in said outer form, and comprising means to embrace and hold in position the reinforcing members for the column, an inner guide, fitted to slide within said reinforcing means, and to embrace and slide upon an inner form, and said inner form. 120
21. In apparatus for constructing concrete columns, the combination of an outer inclosing form, an outer guide, fitted to slide in said outer form, and provided with spacer strips to bear on the interior of said form, said outer guide also comprising means to embrace and hold in position the reinforcing members for the column, an inner guide, provided with spacer strips on the inside and outside, to bear and slide respectively on an inner form and the reinforcing members, and said inner form, and a water excluding coffer surrounding the said outer inclosing form. 125
22. In apparatus for constructing concrete columns, the combination of an outer inclosing form, an outer perforated guide, 130

fitted to slide in said outer form, and provided with spacer strips to bear on the interior of said form, said guide also comprising means to embrace and hold in position the reinforcing members for the column, an inner guide, provided with spacer strips on the inside and outside, to bear and slide respectively on an inner form and the reinforcing members, and said inner

form, and a water excluding coffer surrounding the said outer inclosing form.

Signed by me at Seattle, Washington, this 12th day of May 1913.
